UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

AUTOMATICALLY-THREADING SHUTTLE.

933,497.

Specification of Letters Patent. Patented Sept. 7, 1909.

Application filed March 12, 1909. Serial No. 489,944.

To all whom it may concern:

Be it known that I, EDWARD S. STIMPSON, a citizen of the United States, and resident of Hopedale, county of Worcester, State of Massachusetts, have invented an Improvement in Automatically-Threading Shuttles, of which the following description, in connection with the accompanying drawing, is a specification, like letters on the drawing representing like parts.

10 Shuttles for use in automatic filling replenishing looms are provided with threading devices constructed and arranged to assume automatically control of the thread of a supply of filling inserted in the shuttle and to direct the thread thereafter into the delivery-eye of the shuttle, the entire threading operation being effected while the loom continues in motion.

20 Many forms of threading devices have been proposed and constructed, and operated with signal success, to attain the desired results, but all such devices have been so constructed as to require more or less skilled labor in finishing and adjusting them in order that they may perform their required functions. This is largely due to the fact that cast metal has been utilized in the construction of the threading devices, and the 25 finishing and adjusting steps rendered necessary thereby have resulted in slight variations in the finishing product. These variations, slight though they often are, coupled with the limitations of cast metal, have resulted in practice in variable results with 30 threading devices designed to be duplicates of each other, so that at times annoying and faulty operations have been made manifest. In my efforts to overcome such faulty operations and secure absolute uniformity in the product, with the elimination of the hand 35 operations of finishing and adjusting, I have invented a novel form of threading device, made of plate or sheet-metal and formed or shaped by suitable dies.

40 In my present invention the threading device is made from a single piece of sheet-metal, the blank being cut or stamped out in any suitable manner and then formed by 45 proper dies, so that the threading device made from a given blank can be reproduced indefinitely with the greatest exactitude. Any burs or roughness due to the process of manufacture can be readily removed by 55 tumbling or similar treatment, and the hand operations of finishing and adjusting are

eliminated. I greatly simplify the structure of the threading device by making it in one piece, and reduce the cost of manufacture, and I have embodied in my present invention certain novel features whereby the threading operation is perfected and made certain.

60 The various novel features of my invention will be fully described in the subjoined specification and particularly pointed out in the following claims.

65 In the specification and claims herein that side or wall of the shuttle in which the delivery-eye is located is regarded as the front 70 of the shuttle, and its opposite side is referred to as the rear of the shuttle, while the term "forward", used to indicate direction, means in the direction of or toward the tip of the shuttle at the thread-delivering 75 end thereof.

Figure 1 is a top plan view of the eye end of a shuttle containing my present invention; Fig. 2 is a front elevation thereof; Fig. 3 is a front elevation of the threading 80 device, removed from the shuttle; Fig. 4 is a right-hand end elevation thereof; Fig. 5 is a left-hand elevation of the threading device shown in Fig. 3; Fig. 6 is a perspective view of the threading device; Fig. 7 is a plan 85 view of the blank from which the threading device is formed; Fig. 8 is a perspective view of the metallic liner for the delivery-eye of the shuttle.

90 A is the shuttle, having a bobbin-receiving opening A', Fig. 1, and a is the open delivery-eye provided with a narrow entrance slot a', see Fig. 2, as is common in shuttles of this type, the shuttle-wood being suitably cut out or recessed to receive the threading 95 device and to present a downwardly inclined groove or channel A² leading from the thread passage to the tip of the shuttle, the front wall a² of the channel extending to the entrance slot a', with its top inclined from 100 the highest part to the upper end of the slot, as shown in Fig. 2, to assist the movement of the thread thereto in the threading operation.

105 A metallic, tubular liner e, Fig. 8, having a longitudinal slot e² to register with the entrance slot a', as in Fig. 1, is inserted in the eye a and is cut away at its inner end at e³ for the ready entrance of the thread, an external notch e⁴ being formed in the liner to 110 be engaged by a part of the threading device, to thereby lock the liner in proper position.

I make no claim to the liner in my present application, however, as the same is claimed in connection with the threading device in another application, Serial No. 457,254 filed by me the 12th day of October, 1908, the threading device therein being made of sheet-metal, but in two parts.

C, Fig. 7, is the blank, cut or stamped out of suitable plate metal, such as sheet steel, from which the threading device is formed, said blank being bent up on the dotted lines c^2 to present upturned opposite and substantially parallel front and rear walls b , b' , see Figs. 4, 5 and 6, connected at their lower edges by the flat bottom b^2 , to constitute a thread passage. The edges of the walls at the inner end of the thread passage are shaped to present slightly inclined shoulders 2, and the bottom is prolonged to form a slightly fan-shaped extension 3, which is upturned and bent over against the shoulders, for a purpose to be described, the upper edge of the extension being concaved at 4, Figs. 4, 5 and 6.

Referring to Fig. 7 the left-hand wing or portion of the blank which forms the wall b' is bent over along the line c^2 , such bent part being shaped to form a shield b^3 which is extended frontward over the outer end of the thread passage, said shield being arched or downcurved in the direction of its length and narrowed toward the tip of the shuttle, as at 5, to enter the forward end a^{10} , Fig. 1, of the recess or socket made in the shuttle-wood.

As shown clearly in Fig. 3 the forward end of wall b' extends beneath the shield at 6 to assist in bracing and supporting it in proper position. The edge 7 of the shield extends diagonally from the top of the rear wall frontward, to the front edge 8, at the beginning of the narrowed part 5, and the forward edge 9 is extended in a diagonal direction rearward and downward toward the rear wall of the shuttle, partaking of the downward curve of the part 5 as shown in Figs. 2, 3 and 4.

It will be seen from an inspection of Fig. 4 that the thread passage is substantially rectangular in cross-section, and affords ample room for the thread as it is drawn therethrough, and as the front and rear walls are connected only at their lower edges by the bottom b^2 of the passage said walls can spring or expand laterally, owing to the resiliency inherent in the sheet-metal. I prefer to take advantage of this resiliency to aid in holding the threading device tightly in place, for when it is inserted in the shuttle-body the walls are slightly compressed, so that they will bear firmly and with no appreciable pressure against the adjacent wall of the recess in the shuttle-wood. The forward edge of the wall b is shaped to form an inclined horn 10 terminating at its lower

end in a heel 11, and adjacent thereto the wall is cut out to provide a clearance for the reception of the inner end of the liner e , the upright edge 12 of the cut out part entering the notch e^x to lock the liner in place.

In Fig. 7 the dotted line c^3 indicates the line along which the blank is bent laterally and outwardly, and the substantially triangular head b^4 is formed by the metal at the right of said line Fig. 7, such head being curved over to lie upon the shuttle-body adjacent the slot a' . The forward edge 13 of the head assists in directing the thread into said slot as it is drawn over the top of the wall a^2 around the horn 10 and slides down the latter beneath its heel and into the liner e , said heel performing its usual function of retaining the thread in the lined delivery-eye. The prolonged part b^5 of the head, along the top of wall b , seats in a recess a^{12} in the top of the shuttle, as shown in Fig. 1.

The blank C is shaped to provide for a beak b^6 at the upper end of the horn, in my present invention, and forming the forward termination of the horn and the head b^4 , as will be best seen from an inspection of Figs. 3, 4 and 6, said beak tapering toward its point and being bent to extend rearwardly over the outer end of the thread passage, the point and major part of the beak being turned away from the shuttle-tip, see dotted lines Fig. 1. The forward face of the beak is inclined from top to bottom and is also diagonally disposed with relation to the longitudinal axis of the shuttle, and its upper edge is inclined downward and rearward toward its point from the apex 14 of the beak. By the construction illustrated the thread will slip over the beak readily and off its point into the threading passage during the threading operation.

As clearly shown in Fig. 1 the shield b^3 extends frontward and overhangs the beak, its front edge 8 crossing above said beak at some distance frontward beyond the apex 14 of the beak, and the under edge of the latter is substantially horizontal. The diagonal forward edge 9 of the shield crosses the plane of the under edge of the beak and extends beneath it, as shown in Fig. 4, crossing such plane about at the median line of the thread passage.

Opposite holes 15 in the walls b , b' are arranged to receive the transverse retaining bolt or fastening member M, shown in Fig. 1, passed through the shuttle-wood and crossing the thread passage just above its bottom, securing the threading device in place in the shuttle.

A bent ear 16 on the top of the wall b' at the inner end of the thread passage fits into a suitable recess in the top of the shuttle, this ear serving as a guide for the thread when being drawn into the passage.

A friction member or pad p of felt, flan-

net or other suitable material is forced into piece at the bottom of the thread passage between the exposed part of the bolt M and the upturned part 3 of the passage bottom, 5 at the inner end of the passage, the thread drawing over said friction member and in the concavity 4 made in the upper edge of the part 3. I am enabled to thus provide for a friction member having a relatively large surface to act upon the thread, to provide the necessary tension, and while the pad is securely held in place it can be readily removed when worn out and a fresh one inserted.

15 The inner, upright edge of the wall b above the shoulder 2 is prolonged to form a tapered guard b', which is bent rearward to overhang the inner end of the thread passage and its point '17 is turned forward 20 toward the beak and closely approaches the opposite part of the wall b'. A narrow inlet is thus provided for the entrance of the thread to the passage at its inner end, and to facilitate such entrance of the thread I 25 curve downward the upper edge 18 of the guard from the point adjoining the wall b to the point of the guard, so that the thread slides down over such edge, over the point and into the passage.

30 The under edge 19 of the guard is concaved, Figs. 3, 5 and 6, to act upon the thread as it whips around below the guard and direct it downward, preventing escape of the thread from the inner end of the passage after it has entered it.

35 Should the thread fail to be directed to the delivery-eye of the shuttle it can still be delivered freely and properly around the guard, which then acts as a leader for the thread independently of the eye, the forward curve or turn of the guard being provided for this purpose. Ordinarily, however, the thread slides across the shield onto the head b' and is then drawn beneath the shield, the 40 downcurved and diagonal surface or edge 9 acting to positively engage and depress the thread and draw it downward across the top of the beak b', off its point and then beneath the beak, on the first shot of the shuttle after filling replenishment. The thread is then in the thread passage, below the beak and the guard b', and in the channel A' or lying across its front wall a'. On the next or return shot the thread is drawn around 45 the horn 10 and under the edge 13 of the head b' and is directed under the heel 11 and into the entrance slot a' and passes thence into the liner e, completing the threading of the shuttle. On this second shot the edges 50 9 and 8 of the shield act to direct the thread positively toward the front of the shuttle and away from the apex 14 of the beak, so that the thread cannot by any possibility approach such apex or get behind it and be- 55 tween the apex and the point of the beak.

Thus after the thread has been once drawn under the beak it cannot approach its apex near enough to slide back or rearward and fall off or be shed from the beak.

By the construction herein shown the 70 guard b' is located just as close as possible to the tip of the bobbin in the shuttle, which is of material advantage in effecting prompt control of the fresh filling thread, and the narrow inlet to the thread passage is brought 75 very closely in line with the path of the thread as it leads from the bobbin forward when a fresh bobbin is inserted in the shuttle.

80 So far as I am aware I am the first to construct a threading controlling and directing device complete in itself from a single piece of plate or sheet-metal, formed and shaped from the blank by suitable dies, and comprehending means to direct the thread 85 into the inner and outer ends of the thread passage and thereafter to effectually prevent the escape of the thread therefrom.

Having fully described my invention, what I claim as new and desire to secure by Letters Patent is:—

1. An automatically-threading shuttle having an open delivery-eye and a sheet-metal threading device having opposite upturned walls forming a thread passage, the 95 bottom of the passage being upturned at its inner end, said threading device having a horn terminating in a beak rearwardly extended over the outer end of the thread passage, an upright, curved guard overhanging 100 the inner end of the passage above the upturned portion of its bottom and turned toward the beak, to direct the thread into and prevent its escape from the passage, and also serving to deliver the thread freely independently of the delivery-eye, a front- 105 wardly extended shield overlapping the beak and downcurved toward the shuttle-tip to positively engage and depress the thread below the beak, and a retaining bolt passed 110 transversely through the walls of the thread passage above its bottom.

2. An automatically-threading shuttle having an open delivery-eye and a sheet-metal threading device having opposite upturned walls forming a thread passage, the 115 bottom of the passage being upturned at its inner end, said threading device having a horn terminating in a beak rearwardly extended over the outer end of the thread passage, a guard extended rearward from the upright inner end of the front wall and turned forward toward the beak and having its lower edge overhanging the inner end of the passage above the upturned portion of its bottom, the upper inclined edge of the guard acting to direct the thread into, and its lower edge preventing the escape from, the thread passage, said guard by its forward turn acting as a leader to deliver the 120 125 130

thread from the shuttle independently of the delivery-eye, and a forwardly extended shield overlapping the beak and downcurved toward the shuttle-tip to positively engage and depress the thread below the beak.

3. An automatically-threading shuttle having an open delivery-eye and a sheet-metal threading device provided with opposite, upturned walls to form a thread passage, and with a rearwardly turned beak at the outer end thereof, said beak having its point turned away from the nearer tip of the shuttle, a forwardly extended shield overlapping the beak and acting to positively engage and depress the thread below the beak, the front edge of the shield crossing said beak at a distance in front of the apex of the beak and acting, after the thread has passed under the beak, to hold the thread toward the front of the shuttle and prevent it from being drawn backward over the beak behind the apex thereof, and a longitudinally curved prolongation of the inner upright edge of the front wall turned rearwardly to overhang the passage at its inner end and constitute a guard, the upper edge of the guard being inclined rearwardly to direct the thread into the thread passage and its lower edge being concaved to prevent the escape of the thread from the passage, the longitudinal curvature of the guard enabling it to deliver the thread freely from the shuttle independently of the delivery-eye thereof.

35 4. An automatically-threading shuttle having an open delivery-eye and a longitudinal recess communicating therewith, and a sheet-metal threading device provided with upturned, laterally expansible front and rear walls connected at their lower edges to form a thread passage, said walls bearing firmly against the adjacent faces of the recess to assist in securely positioning the threading device in the shuttle, the front wall having a horn terminating in a beak rearwardly extended over the outer end of the thread passage and also having an upright guard overhanging the inner end of the thread passage and turned at its point toward the beak, to assist in directing the thread into and preventing its escape from the passage, means forwardly extended from the rear wall to overlap the beak and downcurved to positively engage and depress the thread beneath the beak, and a retaining bolt extended through the walls of the threading device and crossing the bottom of the thread passage.

5. A threading device for automatically-threading shuttles, formed from a single piece of sheet-metal and having upturned front and rear walls connected at their lower edges by a flat bottom to constitute a thread passage substantially rectangular in cross-section, the front wall having a horn

terminating in a beak rearwardly extended over the outer end of the thread passage, means extended forward from the rear wall and overlapping the beak and downcurved in the direction of its forward end, to positively engage and depress the thread below the beak in the threading operation, and a tapered prolongation on the upright edge of the front wall, curved in the direction of its length and turned rearward to overhang the inner end of the thread passage and form a fixed guard.

6. A threading device for automatically-threading shuttles, formed from a single piece of sheet-metal and having upturned front and rear walls connected at their lower edges to constitute a thread passage, the front wall having a horn terminating in a beak rearwardly extended over the outer end of the thread passage, a shield extended forward from the rear wall and overlapping the beak and downcurved in the direction of its forward end, to positively engage and depress the thread below the beak in the threading operation, and a prolongation on the front wall extended rearward from its upright edge to overhang the inner end of the thread passage and having its point closely approaching the rear wall and forwardly curved, to form a fixed guard, the upper edge thereof being downwardly curved from the front wall to the point, and its lower edge being concaved.

7. An automatically-threading shuttle having an open delivery-eye and a threading device made of a single piece of sheet-metal having opposite upturned walls forming a thread passage, a beak extended from the front wall rearwardly over the outer end of the thread passage, and a shield extended forwardly from the rear wall, overlapping the beak and downcurved toward the shuttle-tip below the point of the beak to positively engage and depress the thread below the beak.

8. A threading device for automatically-threading shuttles, formed from a single piece of sheet-metal and comprising opposite upturned walls constituting a thread passage, a beak on one wall extended toward the opposite wall over the outer end of the passage, and means on the said opposite wall extended above and overlapping the beak and having a positively acting thread-engaging and depressing surface extended diagonally across the passage and below the beak, and a fixed, upright guard on the upright inner edge of the wall carrying the beak and overhanging the inner end of the thread passage.

9. An automatically-threading shuttle having an open delivery-eye and a threading device formed from a single piece of sheet metal and provided with upturned front and rear walls to form a thread passage,

- means overhanging the outer end of the passage to assume control of and direct the thread to the delivery-eye, and an upright, longitudinally tapered guard extended rearwardly from the front wall to overhang the inner end of the thread passage and having its point turned forward and closely approaching the rear wall of the passage.
10. An automatically-threading shuttle having an open delivery-eye and a threading device formed from a single piece of sheet metal and provided with upturned front and rear walls to form a thread passage, means overhanging the outer end of the
- 15 passage to assume control of and direct the thread to the delivery-eye, and an upright guard at the inner end of the thread passage overhanging the same and rearwardly extended to form, with its point and the rear wall of the thread passage, a narrow inlet for the thread to enter the passage, the inlet being substantially in line with the path

of the thread as it is drawn from the bobbin into the control of the threading device.

11. An automatically-threading shuttle 25 having an open delivery-eye and a threading device made of a single piece of sheet-metal having opposite upturned walls forming a thread passage, a beak on one wall extended toward the opposite wall over the outer end 30 of the thread passage, and means on the said opposite wall extended above and overlapping the beak and having a thread-engaging and depressing surface down-curved toward the shuttle-tip to positively engage 35 and depress the thread below the beak.

In testimony whereof, I have signed my name to this specification, in the presence of two subscribing witnesses.

EDWARD S. STIMPSON.
